CLAIM

The ornamental design for a dosage container, as shown and described.

DESCRIPTION

FIG. 1 is a perspective view of our new design for a dosage container, shown in an open configuration;

FIG. 2 is a right elevation view thereof, shown in an open configuration;

FIG. 3 is a left side elevation view thereof, shown in an open configuration;

FIG. 4 is a front elevation view thereof, shown in an open configuration;

FIG. 5 is a rear side elevation view thereof, shown in an open configuration;

FIG. 6 is a top plan view thereof, shown in an open configuration; and,

FIG. 7 is a bottom plan view thereof, shown in an open configuration.

The even dash-dot broken lines are included for the purpose of illustrating portions of the dosage container that form no part of the claimed design. The long-short broken lines showing boundary lines, which define the bounds of the claimed design, and the space between the boundary lines form no part of the claimed design.
